DOOR CHECK AND HOLD-OPEN

Samuel F. Loria, Dearborn, Mich., assignor to General Motors Corporation, Detroit, Mich., a corporation of Delaware

Application May 27, 1955, Serial No. 511,633

5 Claims. (Cl. 16—85)

This invention relates to a door check and hold-open, and more particularly to a door check and hold-open for an automobile door.

One feature of the invention is that it provides an improved door check and hold-open; another feature of the invention is that it provides a door check and hold-open in which the brackets, links and levers which form the device are all stamped parts, resulting in an economical construction particularly designed for mass production techniques; a further feature of the invention is that the door check and hold-open is so constructed that it may be assembled on the door and body independently of the door hinge means and after the door has been mounted on the body, thereby facilitating manufacture of the automobile; and still a further feature of the invention is that it provides a door check and hold-open including a slotted check link having a cam surface with a detent portion, and a hold-open lever having a follower riding upon the cam surface of the link, abutment of the follower and detent portion of the cam surface providing a yieldable hold-open, and engagement of the link mounting means with an end wall of the slot providing a positive door check.

Other features and advantages of the invention will be apparent from the following description and from the drawings, in which:

Fig. 1 is a fragmentary horizontal section through a portion of an automobile body pillar and door showing the door check and hold-open in top plan view as the parts appear when the door is closed;

Fig. 2 is a section similar to Fig. 1 but with the door open;

Fig. 3 is a section taken along the line 3—3 of Fig. 1; and

Fig. 4 is a section taken along the line 4—4 of Fig. 1.

This door check and hold-open is particularly adapted for use in automobile bodies. Since the brackets, links and levers which comprise the door check and hold-open may all be formed as stamped parts, the device may be economically manufactured according to well known mass production techniques. The door check and hold-open may be mounted on the automobile after the door is hung, and the door check and hold-open is independent of the door hinging means so that manufacture of the automobile body is facilitated, one portion of the door check and hold-open being bolted to the door, another portion being bolted to the body pillar, and the portions being joined after the door is hingedly mounted on the body. After the door is mounted on the body, it may be swung to open position and a slotted link which is mounted on the door may be extended until it fits against a support bracket mounted on the body pillar.

Referring now more particularly to the drawings, an automobile body is designated generally as 10 and a door 11 is hingedly mounted on the body by any conventional hinge means (not shown) to swing between

a closed position shown in Fig. 1 and an open position shown in Fig. 2. That portion of the body illustrated in Figs. 1, 2 and 3 includes a body pillar having a main wall portion 12 forming a door jamb and provided with an opening 13. Inside the pillar there is a reinforcing member 14 which is secured by welding or other means to the main pillar member 12. Externally of the pillar is a recessed jamb facing member 15 which is connected by a pinch weld flange to the outer panel 16 of the body. A support bracket 18 is bolted to the reinforcing member 14 and projects through the opening 13 in the main pillar member 12.

The door 11 has an inner panel 20 which is bent at right angles to form an edge or jamb face portion 21 having an opening 22 opposite the opening 13 in the body pillar when the door is closed. The outer panel 23 of the door is connected by a pinch weld flange to a bent flange 21a at the exterior side of the edge or jamb face portion 21. On the interior of the door there is an inner reinforcement member 25 which is channel shaped, having a transverse portion 26 facing the door jamb and formed with an opening 27 aligned with the opening 22. Internally of the door a bracket 28 is bolted to the inner reinforcement member 25 and a stud or rivet 30 is rigidly mounted on this bracket.

As appears in Figs. 1 and 3, the bracket 18 which is bolted to the body pillar projects into the interior of the door through the openings 22 and 27 when the door is closed. At its free end this bracket is pivotally connected by a rivet 31 to a check link 32 which projects into the interior of the door and which is formed with an elongated slot 33 through which the stud 30 projects. The under-surface 34 of the link 32 is formed as a curved cam surface, being concave in side elevation as the parts appear in Figs. 1 and 2. This cam surface is formed with a detent providing a shoulder 35 near the free end of the link 32, and the cam surface is stepped or offset at 36 adjacent the free end of the link.

A hold-open lever 38 is pivotally mounted inside the door on the stud 30. As shown in Figs. 3 and 4, the stud 30 has a flattened head 37a for holding the parts in position, and a spring washer 39 is located between the head 37a of the stud and the hold-open lever 38. Intermediate its ends the hold-open lever 38 is formed with an offset follower 40 which rides upon the cam surface 34 of the link. A coil spring 41 yieldably urges the follower 40 into engagement with the cam surface 34, one end of the spring being connected to an ear 42 at the free end of the hold-open lever and the other end of the spring being connected to an ear 43 on the bracket 28.

As shown in Fig. 1, the slot 33 extends toward the pivoted end of the link 32 beyond the location of the stud 30 when the door is closed in order to compensate for manufacturing variations in the parts of the door check and hold-open and in the automobile body and door construction. When the door is swung from the closed position of Fig. 1 to the open position of Fig. 2, the stud 30 rides along the slot 33 and the follower 40 rides along the cam surface 34 and over the detent 35 into the offset portion 36 of the cam surface. Because of the yieldable pressure of the spring 41, abutment of the follower 40 with the detent shoulder 35 provides a yieldable hold-open. If the door is swung past the yieldable hold-open position of Fig. 2, the stud abuts the end of the slot 33, thus providing a positive door check.

When the door is swung shut with sufficient force to overcome the spring, the follower 40 rides over the detent and along the curved cam surface 34.

While I have shown and described one embodiment of my invention, it is capable of many modifications. Changes, therefore, in the construction and arrangement

may be made without departing from the spirit and scope of the invention as set forth in the appended claims.

I claim:

1. In a vehicle body construction having door and body pillar members, a door check and hold-open of the character described, including: a check link formed with an elongated slot, said link having a cam surface with a rounded detent portion for providing a yieldable hold-open; means connecting said link to the pillar for pivotal movement about a fixed axis; a stud mounted inside the door, said link extending into the interior of the door and the stud projecting through said slot, engagement of the stud with an end wall of the slot when the door is fully open providing a positive door check; a hold-open lever pivotally mounted inside said door, said lever having a follower riding upon the cam surface of the link; and spring means yieldably urging said follower into engagement with said cam surface, abutment of the follower and detent portion of the cam surface when the door is partially open providing a yieldable hold-open.

2. In a vehicle body construction having door and body pillar members, a door check and hold-open of the character described, including: a check link formed with an elongated slot, said link having a cam surface with a detent portion for providing a yieldable hold-open; means connecting said link to the pillar for pivotal movement about a fixed axis; a stud mounted inside the door and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said follower into engagement with said cam surface, abutment of the follower and detent portion of the cam surface when the door is partially open providing a yieldable hold-open.

3. In a vehicle body construction having door and body pillar members, a door check and hold-open of the character described, including: a bracket mounted on one member; a check link formed with an elongated slot, said link having a cam surface with a detect portion for providing a yieldable hold-open; means connecting said link to said bracket for pivotal movement about a fixed axis; a bracket mounted on the other member; a stud mounted on said last-mentioned bracket and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said

follower into engagement with said cam surface, abutment of the follower and detent portion of the cam surface when the door is partially open providing a yieldable hold-open.

5. In a vehicle body construction having door and body pillar members, a door check and hold-open of the character described, including: a bracket mounted on the pillar and projecting into the interior of the door when the door is closed; a check link formed with an elongated slot, said link having a cam surface with a detent portion for providing a yieldable hold-open; means connecting said link to said bracket for pivotal movement about a fixed axis; a bracket mounted on the interior of the door; a stud mounted on said last-mentioned bracket and projecting through said slot, engagement of the stud with an end wall of the slot when the door is fully open providing a positive door check; a hold-open lever pivotally mounted interiorly of the door, said lever having a follower riding upon the cam surface of the link; and spring means yieldably urging said follower into engagement with said cam surface, abutment of the follower and detent portion of the cam surface when the door is partially open providing a yieldable hold-open.

25 6. In a vehicle body construction having door and body pillar members, a door check and hold-open of the character described, including: a bracket mounted on the pillar and projecting into the interior of the door when the door is closed; a check link formed with an elongated slot, said link having a curved cam surface with a detent portion for providing a yieldable hold-open; means connecting said link to said bracket for pivotal movement about a fixed axis; a bracket mounted on the interior of the door; a stud mounted on said last-mentioned bracket and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said follower into engagement with said cam surface, abutment of the follower and detent portion of the cam surface when the door is partially open providing a yieldable hold-open.

30 7. In a vehicle body construction having door and body pillar members, a door check and hold-open of the character described, including: a bracket mounted on the pillar and projecting into the interior of the door when the door is closed; a check link formed with an elongated slot, said link having a curved cam surface with a detent portion for providing a yieldable hold-open; means connecting said link to said bracket for pivotal movement about a fixed axis; a bracket mounted on the interior of the door; a stud mounted on said last-mentioned bracket and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said follower into engagement with said cam surface, abutment of the follower and detent portion of the cam surface when the door is partially open providing a yieldable hold-open.

35 8. In a vehicle body construction having door and body pillar members, a door check and hold-open of the character described, including: a bracket mounted on the pillar and projecting into the interior of the door when the door is closed; a check link formed with an elongated slot, said link having a curved cam surface with a detent portion for providing a yieldable hold-open; means connecting said link to said bracket for pivotal movement about a fixed axis; a bracket mounted on the interior of the door; a stud mounted on said last-mentioned bracket and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said follower into engagement with said cam surface, abutment of the follower and detent portion of the cam surface when the door is partially open providing a yieldable hold-open.

40 9. In a vehicle body construction having door and body pillar members, a door check and hold-open of the character described, including: a bracket mounted on the pillar and projecting into the interior of the door when the door is closed; a check link formed with an elongated slot, said link having a curved cam surface with a detent portion for providing a yieldable hold-open; means connecting said link to said bracket for pivotal movement about a fixed axis; a bracket mounted on the interior of the door; a stud mounted on said last-mentioned bracket and projecting through said slot, engagement of the stud with an end wall of the slot when the door is fully open providing a positive door check; a hold-open lever pivotally mounted on said stud, said lever having a follower riding upon the cam surface of the link; and spring means yieldably urging said follower into engagement with said cam surface, abutment of the follower and detent portion of the cam surface when the door is partially open providing a yieldable hold-open.
